UNITED STATES PATENT OFFICE.

EDMUND D. GILBERT, DECEASED, BY CLARA A. GILBERT AND JOSEPH DONALD LODGE,
EXECUTORS, OF PHILADELPHIA, PENNSYLVANIA.

BLOW-TORCH.

1,277,905.

Specification of Letters Patent. Patented Sept. 3, 1918.

Application filed January 20, 1917. Serial No. 143,433.

To all whom it may concern:

Be it known that we, CLARA A. GILBERT and JOSEPH DONALD LODGE, citizens of the United States, residing at Philadelphia, in 5 the county of Philadelphia and State of Pennsylvania, are the executors of the last will and testament of EDMUND D. GILBERT, deceased, and that the said EDMUND D. GILBERT invented certain new and useful 0 Improvements in Blow-Torches, of which the following is a specification.

This invention relates to improvements in blow torches and particularly relates to blow torches in which air and gas are used 5 for heating purposes.

The object of the invention is to produce a blow torch which is simple in construction and which can be manufactured at a low cost; a further object of the invention is to 0 provide means for independently regulating the flow of air and gas through the torch; and a further object of the invention is to provide valves in the torch which will remain in a fixed position and which may be 5 readily adjusted by the fingers of the hand in which the torch is held, as will be hereinafter more fully described and claimed.

Referring to the drawings; Figure 1 is a perspective view of the improved blow 0 torch; Fig. 2 is a vertical longitudinal sectional view of the blow torch; and Fig. 3 is a transverse section on line 3—3 Fig. 2.

In the drawings in which like reference characters refer to like parts 1, represents 5 the body portion made of a solid piece of metal, of suitable length to form a handle. The body portion is preferably made elliptical in cross-section, with longitudinal 0 grooves formed along the edges thereof to receive the inlet pipes 2 and 3, which are secured in said grooves formed in the body portion. Thus is formed a rounding and 5 convenient place for gripping the torch in the hand.

5 A central chamber 5 is formed in one end of the body portion, into which is fitted and secured the outlet pipe 6. A smaller outlet pipe 7 is located inside of the pipe 6 and said smaller pipe extends farther into the 0 body portion and is secured in the mouth of the chamber 8 formed in the body portion. An aperture 9 formed in the inlet pipe 2 registers with an aperture 10 in the body portion; a passageway is thus formed between the inlet pipe 2 and the outlet pipe

7. A similar aperture 12 is formed in the inlet pipe 3 and connects with a passageway through the body portion leading into the chamber 5 and to the outlet pipe 6.

Rods 14 and 15 forming valves are fitted 60 into the open ends of the inlet pipes 2 and 3. Said rods are provided for opening and closing the apertures 9 and 12 formed in the inlet pipes 2 and 3. Secured to each of the valve rods 14 and 15, are finger grip 65 plates 17 and 18, by which the rods may be moved in and out by the fingers of the hand holding the torch and thus control the flow of air and gas.

The finger grip plates 17 and 18 are made 70 with concaved edges and projecting corners for better fitting the fingers. The concaved edges of the plates 17 and 18, adjacent to the outlet pipe 6, fit around said pipe and are guided by the pipe; this holds the rods 75 14 and 15 rigid and prevents the said plates from turning.

A sleeve 20, is slidably mounted upon the outlet pipe 6 and may be secured by the set-screw 21 in a position to limit the outward 80 movement of the finger grip plates 17 and 18. When the valve rods 14 and 15 have been adjusted to the desired position the sleeve 20 may be moved along the outlet pipe 6 until it strikes one of the finger grip 85 plates and when the sleeve is secured in this position it will act as a guide for resetting the valve rods in the same position after they have been moved inwardly to close off the flow of air and gas, and it is desired to 90 again open the valves to the same adjustment.

The ends of the inlet pipes 2 and 3, which receive the valve rods, project beyond the body portion and the free ends of the pipes 95 are provided with longitudinal slots 22 which permit the metal forming the ends of the pipes to be contracted and tightly impinge against the valve rods to prevent the pressure of the medium in the inlet pipes 100 from moving the valve rods.

Flexible connections 23 and 24 are attached to the inlet pipes 2 and 3 and supply air and gas to the torch. The pipe 2 is preferably used for the air supply and the pipe 105 3 for the gas supply.

Having thus described the invention we claim and desire to secure by Letters Patent:—

1. In a device of the character described 110

comprising, a body portion, inlet pipes secured to the body portion, said inlet pipes extending throughout the length of the body portion to form a hand grip, an outlet pipe secured in the body portion and said body portion having passageways formed therein leading from the inlet pipes to the outlet pipe.

2. In a torch the combination, of a body portion of elliptical cross section and having longitudinal grooves formed therein, inlet pipes secured in the said grooves formed in the body portion, outlet pipes secured in one end of the body portion, said body portion having passageways formed therein leading from the inlet pipes to the outlet pipes and valves in the inlet pipes.

3. In a torch the combination, of inlet pipes, a body portion of sufficient length to form a hand grip, said body portion being approximately elliptical in cross section with longitudinal grooves formed in opposite sides thereof in which grooves said inlet pipes are secured to complete the elliptical formation of the hand grip, an outlet pipe secured in the body portion and said body portion having passageways formed through the same.

4. In a torch the combination, of a body portion, inlet pipes secured to opposite sides of the body portion, an outlet pipe secured in the body portion and located centrally between the inlet pipes, rods slidably mounted in the inlet pipes, finger grip plates upon

35 the ends of the said rods, said finger grip plates having portions thereof embracing the said outlet pipe and guided by the latter.

5. In a torch the combination, of a body portion, inlet pipes secured to opposite sides of the body portion, an outlet pipe secured in the body portion located centrally between the inlet pipes, valve rods slidably

mounted in the inlet pipes, finger grip members on the valve rods, and a stop adjustably secured upon the outlet pipe for engaging 45 the finger grip plates on the valve rods.

6. In a torch, the combination, of a body portion, inlet pipes secured to opposite sides of the body portion, the ends of the said inlet pipes projecting beyond the end of the 50 body portion, valve rods slidably mounted in the inlet pipes, said projecting ends of the inlet pipes having longitudinal slots formed therein to permit the ends of the pipes to be contracted and impinge against 55 the valve rods, outlet pipes secured in the body portion, and passageways formed in the body portion connecting the inlet pipes with the outlet pipes.

7. In a torch the combination, of a body 60 portion, inlet pipes secured to the body portion, chambers formed in the body portion communicating with the inlet pipes, outlet pipes secured in the body portion and communicating with the chambers in the body 65 portion, valve rods slidably mounted in the inlet pipes, finger grip plates upon the valve rods, said finger grip plates having concaved sides to embrace the outlet pipe located between them, a sleeve adjustably secured upon 70 the outlet pipe forming a stop, and contracted ends upon the inlet pipes to impinge against the valve rods.

In testimony whereof we affix our signatures in presence of two witnesses.

CLARA A. GILBERT,
JOSEPH DONALD LODGE,
*Executors of the last will and testament of
Edmund D. Gilbert, deceased.*
